(57) **CLAIM**

The ornamental design for a loudspeaker, as shown and described.

DESCRIPTION

FIG. 1 is a top, front, and right side isometric view of a loudspeaker, showing my new design.

FIG. 2 is a top plan view of the loudspeaker in FIG. 1.

FIG. 3 is a front elevation view of the loudspeaker in FIG. 1.

FIG. 4 is a rear elevation view of the loudspeaker depicted in FIG. 1.

FIG. 5 is a left side elevation view of the loudspeaker depicted in FIG. 1.

FIG. 6 is a right side elevation view of the loudspeaker depicted in FIG. 1; and,

FIG. 7 is a bottom plan view of the loudspeaker depicted in FIG. 1.

The broken lines in the figures illustrate the portions of the design that form no part of the claimed design.
